UNITED STATES PATENT OFFICE.

CLAUDE L. MANVILLE, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

AIR AND VARNISH HEATER.

1,279,135.

Specification of Letters Patent. Patented Sept. 17, 1918.

Application filed September 4, 1915. Serial No. 49,001.

To all whom it may concern:

Be it known that I, CLAUDE L. MANVILLE, a citizen of the United States, residing at North Tonawanda, in the county of Niagara 5 and State of New York, have invented new and useful Improvements in Air and Varnish Heaters, of which the following is a specification.

This invention relates to a method of and 10 an apparatus for heating varnish and air in the use of the air-brush system of applying varnish to woodwork.

Heretofore, means have been provided for heating either the air or the varnish, but 15 the results have proved unsatisfactory. When the varnish alone is heated, the cold air chills and thickens it, preventing its even flow and producing a comparatively rough or pebbled coating. When the air 20 alone is heated, it fails to break up the varnish granules sufficiently to produce a smooth surface, such as required, for example, for piano cases.

The object of my invention is the provision of a simple and inexpensive apparatus by which the varnish and air will be heated practically to the same degree, in order to cause the varnish to flow more evenly from the air brush and spread it 25 over the woodwork in a finer and more uniform condition and in comparatively smooth coats, thus requiring less rubbing of the successive coats or applications of varnish and effecting a corresponding saving in 30 time.

In the accompanying drawings:

Figure 1 is a side elevation of the improved apparatus, partly in section. Fig. 2 is a cross section on line 2—2, Fig. 1.

Similar characters of reference indicate 40 corresponding parts in both views.

1 indicates a tank or reservoir which is adapted to be partly filled with water and which in the example shown in the drawings is externally screw threaded at its ends to receive internally screw threaded unions or couplings 2 which engage caps 4. Between the opposing ends of the reservoir and these caps, suitable packings 5 are interposed. 1^a is the valved water-inlet pipe 45 of the reservoir.

• Passing longitudinally and preferably centrally through the reservoir 1 is a steam pipe 6 which serves to heat the water there-

in. Steam is supplied to this pipe from any 55 suitable source and the pipe has valves 7 and 8 for controlling the passage of the steam through it.

Immersed in the water of the reservoir are two pipes or coils 9 and 10, one for 60 heating varnish and the other for heating air. The inlet ends of these coils pass through one of the caps of the reservoir and are connected respectively with an air compressor or compression tank and a varnish supply tank, not shown, while their opposite ends pass through the other cap of the reservoir and are connected with the usual inlets of the air brush, so that the varnish is sprayed and projected against 70 the surface to be varnished in a common manner. The air pipe has a valve 11 and the varnish heating pipe or coil has valves 12 and 13 for regulating the passage of the fluid through them.

14 indicates a water gage connected with the reservoir, and 15 a thermometer also connected therewith for observing the temperature of its contents.

The hot water in the reservoir in turn 80 heats the varnish and air heating coils 9 and 10, and by locating the steam pipe 6 centrally in the reservoir, and the coils 9 and 10 on opposite sides thereof, a uniform heating of both coils and of the varnish and 85 air passing through them is insured. While this central arrangement of the steam pipe is desirable, it is not essential.

In using varnish, lacquers and japs with an air brush, it is very important that 90 the air and varnish should be heated to the same temperature, which is accomplished by this apparatus. Being thus heated the varnish flows out more freely and avoids the objectionable stippled or pebbled effect ordinarily produced by the air brush. The several coats applied to the woodwork are therefore smoother and finer-grained, requiring less rubbing to produce the desired 95 ultimate finish and effecting an important 100 saving in time and labor. Sags or runs which are often caused by the air brush are also avoided by the use of this heater. The varnish and japan can also be used without thinning with turpentine, thereby saving 105 one or two coats of varnish on case-work of all kinds.

Furthermore, the air pressure may be

materially reduced by the use of this heater, as the varnish granules are broken up more readily in a heated state and therefore yield to a lighter air pressure which is less likely to produce a stippled effect than a comparatively high pressure.

I claim as my invention:

1. An air and varnish heater for air brushes, comprising a water reservoir, means for heating the water therein, and separate air and varnish heating coils both arranged in said reservoir, whereby the air

and varnish supplied to the air brush are heated to substantially the same temperature.

2. An air and varnish heater for air brushes, comprising a water-reservoir, a steam pipe located centrally therein, air and varnish heating coils located in the reservoir on opposite sides of said steam pipe and extending through the heads of the reservoir, and controlling valves arranged in said coils outside of the reservoir.

CLAUDE L. MANVILLE.
